UNITED STATES PATENT OFFICE

ROSSWELL W. THOMAS, OF BARTLESVILLE, OKLAHOMA, ASSIGNOR TO PHILLIPS PETROLEUM COMPANY, OF BARTLESVILLE, OKLAHOMA, A CORPORATION OF DELAWARE

DEHYDRATION OR COOLING OF AIR OR OTHER GASES

Application filed August 29, 1929. Serial No. 389,220.

This invention relates to improvements in the dehydration or cooling of air, low calorific value gas or a finished gas.

- In my application Serial No. 362,436, filed 5 May 11, 1929, I have disclosed a system in which the low temperature created due to heat absorption by the expansion of light paraffin hydrocarbons or similar gases, is utilized to dehydrate air or the like, which is 10 subsequently mixed with the hydrocarbons to produce a combustible gaseous mixture. In that system, the hydrocarbons and air flow adjacent to one another and out of contact in a heat exchanger. 15 The primary object of the present invention is to improve such system and this I accomplish mainly by bringing the hydrocarbons and the air or other gas into direct contact while the hydrocarbons are expanded, so that the heat absorbed causes refrigeration and precipitation of the aqueous moisture contained in the air or the like.

Another object of this invention is to provide a system in which the air or other gas 25 and the hydrocarbon fluid are pumped in such manner that the volume of the air or other gas is utilized to vary the speed or stroke of the hydrocarbon pump, whereby an increased or decreased amount of hydrocarbon fluid is 30 forced through the system as the volume of the air or other gas increases or decreases.

A further object is to provide an apparatus for this purpose in which the hydrocarbon pump is arranged at a lower level than 35 the hydrocarbon supply tank so that the hydrocarbon pump is always under the influence of the static head produced by the liquefied hydrocarbon fluid.

Another object is to furnish a gas making 40 system or the like in which the ice formed due to the expansion of the hydrocarbon fluid may be readily removed from the system without interfering with the continuous operation of the latter.

45 With the foregoing objects outlined and

with other objects in view which will appear as the description proceeds, the invention consists in the novel features hereinafter described in detail, illustrated in the accompanying drawing, and more particularly 50 pointed out in the appended claims.

The drawing is a diagrammatic view of one embodiment of my improved apparatus for use in carrying out the method.

From the following detailed description 55 it will be observed that I have provided a novel method of carbureting air or low calorific value gas with a volatile paraffin hydrocarbon fluid, such as butane, propane, ethane or mixtures of the same, or similar hydrocarbons, and at the same time utilizing the latent heat of vaporization of the liquefied hydrocarbon fluid to refrigerate and dehydrate the air or low calorific value gas. The difference between my present proposal and the 60 disclosure in the above-mentioned patent application is that in the present case the vaporizing hydrocarbon fluid is in direct contact with the stream of air or low B. T. U. gas, and not separated therefrom in a heat ex- 65 changer or other device.

I propose that air or any other suitable base gas be supplied at any pressure from atmospheric up to say 100 pounds gauge, by any suitable means, such as a rotary or reciprocating compressor or blower 1, and that the air or gas stream discharged from the pressure pump be measured through a rotary or positive displacement meter 2, or even through an orifice or Venturi type meter, with the meter so arranged (for instance by means of a conduit 3) in communication with a hydrocarbon pump 4, that the strokes or the movement of the liquid pump will be proportional to the air or gas flow. Obviously, a correction for absolute pressure of the air or gas stream must be incorporated, however, in a great many systems the apparatus can work at a constant pressure, thus eliminating this variable.

The hydrocarbon pump 4 may be of any suitable design and will preferably be positioned adjacent to and just below the storage tank 5 which contains the liquefied paraffin hydrocarbon gases. The pump will thus have a positive suction head in addition to the vapor pressure of the hydrocarbon fluid, or in other words, the pump will be submerged below the normal liquid level, thus assuring complete filling of its cylinders or clearance spaces and consequent accurate metered delivery of the liquid carburent.

A back pressure valve 6 is preferably installed in the hydrocarbon pump discharge line 7 so that the pump will work against a discharge pressure higher than the vapor pressure of the hydrocarbon fluid under normal operating conditions. This will prevent vaporization in the pump 4 and its discharge chamber, which vaporization or partial vaporization would perhaps otherwise interfere with the accuracy of proportioning between the pump carburent and the base gas or air.

The latent heat of vaporization of the liquefied carbureting medium will in one or the other of the chambers 9 and 10, be supplied by the stream of base gas or air flowing through the discharge line 8, resulting in refrigeration of the mixture to such a low degree that practically complete dehydration will be accomplished. Calculations are available on the extent of such refrigeration for any given set of conditions, but it is enough to say that the degree of refrigeration even on very low calorific value finished mixtures, will be sufficiently low to accomplish the dehydrating effect desired.

The temperature level will in fact be, in practically all cases, below the freezing point of water with the possible exception of carburation of a base gas over pressures from 50 pounds gauge upwards; the exact pressure being dependent, of course, upon the relative percentages of base gas and carbureting medium, and also on the particular carbureting medium used.

In order to allow for the accumulation of ice and its subsequent removal, I preferably mix the carburent and base gas or bring these fluids into contact, in either one or the other of the two expansion chambers 9 or 10, wherein the liquid from the pipe 7 will be injected through the end 11 of the pipe into the flowing base gas stream entering through the end 12 of the pipe 8; only one chamber being used at a time and suitable valves 13 being interposed in the pipe lines to properly control the flow of the fluids.

With such an apparatus, a cycle of operation can be established in which, for instance, one chamber will be used for one week and the second chamber for the subsequent week, during which latter period the first chamber would be allowed to thaw out and the water

be drained therefrom through a suitable discharge pipe 14.

The chambers 9, 10 may be entirely separate from one another or may be adjacent to each other with an insulation partition 15 arranged between the same, and both of these chambers may be connected by valved branches 16 to a common outlet pipe 17 which leads the resulting dehydrated gaseous mixture to a suitable place of storage or disposal. 75

By properly proportioning the size of the expansion or refrigerating chambers 9 and 10 and by controlling the cycle of operation, no difficulty will be experienced from the removal or non-removal of the frozen moisture 80 content. The alternation from one carbureting chamber to the other can be accomplished manually by means of the valves, or automatically, but in most cases manual operation will be desirable inasmuch as the 85 changes will be very infrequent.

I do not wish to be limited to the use of a plurality of expansion or refrigerating chambers 9, 10, as I am aware that similar results may be accomplished by the use of a 90 single chamber only.

Neither do I wish to limit this application to the dehydrating of air or other base gas used in making a combustible mixture, as it is obvious that the same inventive idea may 95 be used in the cooling or refrigeration of a base gas or a finished gas in various types of gas manufacturing plants and in gas compressing and cooling operations. In one installation for peak load purposes in which 100 substantially pure butane is employed, such hydrocarbon is injected by hand-controlled means into the discharge lines from a two-stage carbureted water gas compressor. In 105 that case, the after-cooler capacity was insufficient and utilization of the latent heat of vaporization of the liquid butane carburent was very effective in affording additional cooling, thus eliminating the necessity of additional capital investment in after-coolers 110 and, incidentally, this liquid injection resulted in an increased capacity of the discharge pipe line from the plant to the points of distribution in the city, due to a reduction in the temperature of all of the gas being 115 pumped through the pipe lines. This, in turn, reduced the power cost at the compressor station.

From the above it will be noted that the gist of my invention resides in the contacting 120 of a liquefied hydrocarbon gas with any other suitable gas for the purpose of utilizing the latent heat of vaporization of the hydrocarbon fluid to refrigerate and/or dehydrate the gas with which it is contacted. 125

The terms and expressions employed herein are used as terms of description and not of limitation, and there is no intention in the use of said terms and expressions to exclude any of the features shown and described or 130

portions thereof, but it is recognized that various modifications are possible within the scope of the invention claimed.

What I claim and desire to secure by Letters Patent is:

1. In a gas manufacturing method, pumping a stream of gas, also pumping a stream of a normally gaseous hydrocarbon fluid in liquid state, utilizing the flow of one of said streams to vary the pumping of the other stream, directly contacting the streams in such manner that the hydrocarbon fluid in vaporizing will dehydrate and refrigerate the gas stream, separating the moisture from the combined streams, and discharging the combined streams through a common passageway.
2. In a gas manufacturing method, storing a normally gaseous hydrocarbon fluid in liquid condition in a storage chamber, pumping such fluid from the bottom portion of the storage chamber and thus interposing the static head of the fluid on the pump, subsequently allowing the hydrocarbon fluid to vaporize, and mixing the same during said vaporization with a gas to dehydrate and refrigerate the latter.
3. In a gas manufacturing method, storing a normally gaseous hydrocarbon fluid in liquid condition, pumping such fluid from storage past by back pressure barrier, subsequently vaporizing the fluid and mixing a gas with the fluid during such vaporization to dehydrate and refrigerate said gas.
4. An apparatus of the character described, including a closed storage tank for storing a normally gaseous hydrocarbon fluid in liquid condition, a liquid pump communicating with said storage tank and arranged below the same, a pipe line leading from the pump, a nozzle at the end of said pipe line, a vaporizing chamber, the nozzle discharging into the vaporizing chamber, a conduit leading into said vaporizing chamber, means for forcing a gas into said conduit, means for discharging a gaseous mixture from the vaporizing chamber, and means for discharging water from the vaporizing chamber.
5. A method of manufacturing a gaseous fuel composition, comprising directly mixing a flowing stream of a moist base gas with a flowing stream of a normally gaseous hydrocarbon fluid while the latter is vaporizing from a substantially liquid state into a gaseous state, and thereby causing the base gas to furnish the latent heat of vaporization for said fluid and the fluid in vaporizing to condense the moisture from the base gas, and discharging the mixture of dehydrated base gas and fluid from the zone of condensation, and separately discharging the condensate from said zone.
6. A method of the character described, comprising mixing a stream of moist oxygen containing gas with a stream of normally

gaseous hydrocarbon fluid alternately in separate chambers while the fluid is undergoing vaporization from a substantially liquid state to a gaseous state, causing said stream of gas to furnish the latent heat of vaporization for the stream of fluid while the latter is vaporizing causes freezing of the moisture from the stream of gas, and removing the moisture from each chamber while mixing and vaporization is taking place in the other chamber.
